US00D666988S

(12) **United States Design Patent**
Meurer

(10) **Patent No.:** US D666,988 S
(45) **Date of Patent:** ** Sep. 11, 2012

(54) **COMMUNICATION DEVICE**(75) Inventor: **Eberhard Meurer**, Schwenningen (DE)(73) Assignee: **S. Siedle & Soehne, Telefon—und
Telegrafenwerke Ohg**, Furtwangen
(DE)(**) Term: **14 Years**(21) Appl. No.: **29/392,273**(22) Filed: **May 19, 2011****Related U.S. Application Data**

(62) Division of application No. 29/324,171, filed on Sep. 8, 2008.

(30) **Foreign Application Priority Data**

Mar. 7, 2008 (EM) 893 482

Primary Examiner — Carla Wright(74) *Attorney, Agent, or Firm* — Rothwell, Figg, Ernst & Manbeck, P.C.(57) **CLAIM**

The ornamental design for a communication device, as shown and described.

DESCRIPTION

FIG. 1 shows a front view of the communication device;
FIG. 2 shows a back view of the communication device;
FIG. 3 shows a bottom view of the communication device;
FIG. 4 shows a top view of the communication device;
FIG. 5 shows a side elevation view of the communication device;
FIG. 6 shows a perspective view of the communication device; and,
FIG. 7 shows a side elevation view of the second side of the communication device.
In the drawings, the broken lines depict unclaimed environment. The broken lines form no part of the claimed design.
